UNITED STATES PATENT OFFICE.

JAMES W. HILL, OF PEORIA, ILLINOIS, ASSIGNOR TO THE PEORIA PULLEY AND WHEEL COMPANY, OF SAME PLACE.

MOLD FOR CASTING WHEELS.

SPECIFICATION forming part of Letters Patent No. 408,105, dated July 30, 1889.

Application filed February 18, 1889. Serial No. 300,362. (No model.)

To all whom it may concern:

Be it known that I, JAMES W. HILL, a citizen of the United States, residing at Peoria, in the county of Peoria and State of Illinois, have invented certain new and useful Improvements in Molds for Casting Wheels, &c., of which the following is a specification.

My invention relates to improvements in molds for casting wheels and pulleys of different widths; and it consists in certain features of construction, to be hereinafter described, and then particularly pointed out in the claims.

In order that my invention may be fully understood, I will proceed to describe the same, reference being had to the accompanying drawings, in which—

Figure I is a vertical sectional view of my invention, showing the parts set up ready for casting. Fig. II is a vertical sectional view of the internal removable parts withdrawn from the mold, the lower sections of the sectional segments remaining in place, and Fig. III is a vertical sectional view of the remaining parts. Fig. IV is a plan view of the mold, the internal removable parts being withdrawn. Fig. V is a top view of Fig. II. Fig. VI is a perspective view of the lower wedge-ring. Figs. VII, VIII, and IX are details. Fig. X is a vertical section through the lower casing-ring. Fig. XI is a vertical sectional view of the internal parts necessary to replace those shown in the other figures when the rim is to be cast on two series of spokes. Fig. XII is a perspective view of the support for the inner ends of the spokes shown in Fig. XI. Fig. XIII represents another form of device for disengaging the hooked rods from the lower wedge-ring, the parts being shown in dotted lines. Fig. XIV is an underside view of the bed-plate and said disengaging device turned up at an angle of about forty-five degrees.

The casing and support of the mold are the same when the rim is to be cast onto either a single or double set of spokes, while the internal parts in both instances are different in most respects.

I will first describe the mold as a whole

when used for casting a rim onto a single series of spokes. 50

1 represents the base, and 2 the legs, on which it is supported.

3 is a broad ring, (which I will designate the "base-ring,") through which are passed 55 bolts 4, which also pass through the legs and the outer edge of the base 1, thus securing the legs to the latter. Onto the lower ends of these bolts are screwed nuts 5. These bolts also pass through blocks or thimbles 6, 60 interposed between the base-ring 3 and the base 1. Placed over these blocks and resting just upon the base 1 are collars 7, between which and said blocks are driven wedges 8, for a purpose to be hereinafter stated. At 65 the inner edge of the base-ring 3 extends upward, as 3^a, (see Fig. X,) and in this extended or enlarged portion is formed a dovetail groove 3^b, which is inwardly and upwardly inclined. This groove is filled with a suitable filling of refractory material *a*, that is of low conductivity of heat and that is not easily destroyed by the molten metal—such as fire-clay, asbestos, black-lead, &c. The enlarged inner side of the base-ring 3 fits 70 into a rabbet-groove formed in the under side of a ring 9, which in turn fits into a rabbet-groove formed in the under side of a similar ring 10, which rests upon it, and these rings 75 3, 9, and 10, together with an upper ring 11, fit into a rabbet-groove, in the under side of which the top of the ring 10 fits, constitute the casing of the mold. At its lower inner edge the upper ring 11 is provided with a dovetail groove 12, which is inwardly and 80 downwardly inclined, and this groove is also filled with a refractory substance similar to that in the groove 3^b in the base-ring. The exposed surfaces of these refractory fillings may be either curved, inclined, or otherwise 85 conformed, according to the kind of edge the rim of the wheel is to have. Formed integrally with the top ring 11, and extending upwardly therefrom, are the pouring-gates 13. Vents 14 are also formed in this ring. 90

Screwed into the center of the base 1 is a standard 15, onto the lower end of which is screwed a nut 16. At the upper end of this 95

standard is formed a disk-shaped support 17, and extending from the upper end of said standard downwardly is a bore 15^a, which at its lower end opens outwardly through the 5 side of the same.

The internal parts of the mold proper consist of segments 18, having wedge-shaped ends, (and so I will term them "wedge-segments,") and sectional segments horizontally divided, 10 the upper sections being numbered 19 and the lower sections 20. These segments are arranged alternately around the inside of the mold and they form the inner face of the rim of the wheel being cast. The lower ends of 15 the lower sections 20 are provided with in-turned flanges 20^a, which afford a better support for these sections than were they formed without them. Now the purpose of the collars 7, before referred to, is to retain these 20 lower sections in position fixedly in the mold, and to this end the collars are provided with screw-threaded pins 7^a, which are screwed into these sections, and when the wedges 8 are driven between the collars and the thimbles 6 these sections 20 will be held rigid, 25 as stated, as they are not intended to be removed in practice. The upper ends of the lower sections and the lower ends of the upper sections are provided with in-turned flanges 30 21, which are grooved transversely at 21^a to receive the outer ends of the spokes. The inner ends of the spokes rest upon the disk-shaped support 17. Connecting the lower sections 20 to the standard 15 are spiral 35 springs 22.

The bore 15^a of the standard 15 constitutes a socket to receive removably a post 23, projecting centrally from the under side of a disk 24. The purpose of leading the lower 40 end of this bore or socket outwardly is, that if any dirt be lodged therein it will be forced out by the insertion of said post. Connecting the upper sections 19 to the disk 24 are spiral springs 25.

45 There are two rings—an upper one 26 and a lower one 27—with wedges 26^a and 27^a cast on the outside thereof, the inclined faces of which engage, respectively, the upper and lower inclined faces of the wedge-segments.

50 The upper wedge-ring 26 has hooks 28, which engage with projections 29 on the upper sections 19 of the sectional segments, while the upper ends of their wedges 26^a engage with the lips or flanges 30 on the upper ends of the wedge-segments 18, and thus when the 55 lifting-chains 31 are raised by suitable power these parts are lifted from the mold. These lifting-chains are connected with the hooks 28.

A pair of rods 32, screw-threaded at their 60 lower ends and having eyes at their upper ends, screw into lugs 32^a on the lower wedge-ring and extend up to the top of the mold, and are used in setting up the mold. Hooks and chains are attached to their upper ends 65 and power is applied by pulley-blocks or any well-known means (not necessary to be shown) to lift the lower wedge-ring into position, ex-

70 panding the lower ends of the segments 18 and 20 to place. The abutting edges of the wedge-segments 18 and the alternate sectional segments are beveled, so that when the wedge-segments are forced out they will also force out the alternate sectional segments. The rods 32 are held in the above-stated manner until the two rods 33, which are 75 screw-threaded at their upper ends to receive nuts 33^a, by which they are secured to ring 26, and at their lower ends are hooked, (the hooks 34 engaging the under side of the lower wedge-ring,) are adjusted and tightened by 80 means of said nuts. These hooked rods 33 draw the two wedge-rings toward each other, and thereby expand the segments against the bottom and top outer rings of the mold. The hooked ends of the rods 33 pass through the 85 base or bed-plate of the mold, and one of them is connected with a tripping-treadle 35 by means of a chain 36, so that it may be disengaged from the lower wedge-ring by pressing the treadle with the foot, and the 90 other rod 33 may be released simultaneously by hand, and the removable parts may then be lifted. Another form of device is shown 95 in Figs. XIII and XIV for this purpose. The hooked end of one of the rods 33 is shown in engagement with a projection *b* on a bar *a*, which is arranged underneath the bed-plate and extends from side to side, one end sliding in a housing *c* and the other end being pivoted to one end of a bell-crank *d*, which 100 is pivoted to the under side of the bed-plate. The hooked end of the other rod 33 is engaged with the other end of the bell-crank. The end of the bar that slides in housing *c*, it will be seen, projects beyond the bed-plate. 105 When this end is struck by a hammer, the force of the blow, acting through this device, will detach both hooks from the lower wedge-ring simultaneously. Connecting the upper ends of the segments is a chain 37, which 110 passes completely around the inner side of the mold and holds the segments together side by side when they are lifted. Dowel-pins 38 on the lower ends of the upper sections of the sectional segments fit into holes 115 in the upper ends of the lower sections. The segments are grooved at 38^a, so as to form a rib on the inner side of the rim.

In practice a quantity of the intermediate outer rings 9 and 10 are provided, of different 120 heights, smaller ones being used when a narrow rim is to be cast. (See Fig. III.) This will necessitate the raising of the outer base-ring 3 according to the height of the intermediate rings, which is done by interposing 125 more thimbles or blocks 6 between it and the bed-plate. I do not restrict myself to the number of outer rings employed at a single casting, as the number may be varied according to the size of pulley to be cast. The other 130 parts of the apparatus are suited for all widths of pulleys.

Figs. XI and XII show means for casting pulleys with two sets of arms. Each alter-

nate segment is cut horizontally on the same plane for one set of spokes. The remaining segments are cut horizontally on a higher or lower plane for the other set of spokes. The 5 other parts of the mold, with the following exceptions, remain the same. The central standard 15 has at its upper end a disk 39, having on its rim a series of projections 40, forming extensions of the flange 41. The 10 flange 41 between the projections is notched to receive the inner ends of one series of spokes, and the upper ends of the projections 40 are provided with notches 42 to receive the inner ends of the other series of spokes. Provision 15 for four arms in each series is shown; but I do not limit myself to this number. For holding the segments in line long rods 43 are employed instead of dowel-pins, and these pass through flanges 44 on the inner face of each segment, two or more being employed. This is considered essential where every segment is cut in two horizontally. In this form of mold the top sections of each segment only are removed after the pulley is cast.

25 Having thus described my invention, the following is what I claim as new therein and desire to secure by Letters Patent:

1. In a mold for wheels and pulleys, the combination of the internal parts and the 30 built-up casing composed of upper and adjustable lower and intermediate interchangeable rings, said lower ring having means of vertical adjustment, whereby rims of different widths may be cast, substantially as set forth.

35 2. In a mold apparatus, the combination, with the bed-plate and internal parts, of the outer interchangeable rings of different widths constituting the casing, interposed block or blocks between the lower ring and 40 the base-plate, and a fastening for securing the lower ring, blocks, and base-plate together, substantially as set forth.

3. In a mold apparatus for wheels and pulleys, the combination, with the bed-plate and 45 internal removable segments, of the casing made up of a series of interchangeable rings of different widths, and interposed interchangeable blocks between the lower ring and the base-plate, whereby rims of different 50 widths may be cast, substantially as set forth.

4. In a mold apparatus, the combination, with the bed-plate and the internal parts, of the 55 casing consisting of upper and lower rings and interchangeable blocks interposed between the lower ring and the base-plate, substantially as and for the purpose set forth.

5. In a mold apparatus, the combination, with the bed-plate and the internal parts, of 60 the outer interchangeable rings constituting the casing, interchangeable interposed blocks between the lower ring and the bed-plate, bolts passing through the bed-plate, blocks, and the lower ring, and nuts screwed onto the 65 lower ends of the bolts, substantially as set forth.

6. In a mold apparatus, the combination of the casing and the internal segments, a series of alternate sections being divided horizontally and provided with grooves to receive the 70 spokes, substantially as set forth.

7. In a mold apparatus, the combination of the casing, the bed-plate, the internal segments, each alternate one being divided horizontally and provided with grooves to receive 75 the spokes, interposed blocks between the casing and the bed-plate, suitable means for securing the blocks to the bed-plate, collars fitting over said blocks and having screw-threaded pins screwing into the lower sections of the divided segments, and wedges driven between the collars and blocks, substantially as and for the purpose set forth.

8. In a mold apparatus, the combination of the casing consisting of upper and lower 85 rings and interchangeable intermediate rings, means for supporting the casing at different heights, and the intermediate segments, every alternate one of which is horizontally divided and provided with grooves to receive the 90 spokes, substantially as and for the purpose set forth.

9. In a mold apparatus, the combination of the casing, the wedge-segments, the alternately-arranged divided segments provided 95 with grooves to receive the spokes, and means for engaging the inclined portions of said wedge-segments and expanding all the segments outwardly, substantially as set forth.

10. In a mold apparatus, the combination of the casing, the wedge-segments, the alternate divided segments provided with grooves to receive the spokes, the upper and lower wedge-rings adapted to engage the inclined portions of the wedge-segments, and devices for forcing 105 said wedge-rings toward each other, substantially as set forth.

11. In a mold apparatus, the combination of the casing, the whole segments, and the alternate divided segments provided with 110 grooves to receive the spokes, a central standard, and springs connecting the lower portions of the divided segments to said standard, substantially as set forth.

12. In a mold apparatus, the combination 115 of the casing, the whole segments, the alternate divided segments provided with grooves to receive the spokes, a central standard having a socket at its upper end, a disk at its top, an upper disk, having a post projecting 120 downwardly and fitted loosely in said socket, and springs connecting said standard and upper disk to the divided segments, substantially as set forth.

13. In a mold apparatus, the combination 125 of the casing, the whole segments, the alternate divided segments provided with grooves to receive the spokes, a central standard having a socket or bore extending downwardly and out through its side, a disk at the top of 130 the standard, an upper disk having a post projecting downwardly and fitted loosely in

- said socket or bore, and devices connecting said standard and upper disk to the divided segments, substantially as set forth.
14. In a mold apparatus, the combination of the casing, the whole segments the alternate divided segments provided with grooves to receive the spokes, the upper and lower inner rings having means for securing them together and forcing said segments outwardly, 10 projections on the upper ring, and projections on said segments, with which the latter engage, substantially as and for the purpose set forth.
15. In a mold apparatus, the combination of the casing, the inner segments having projections, the lifting-chains, a ring suspended thereby, and projections on said ring engaging the projections on the segments, substantially as set forth.
16. In a mold apparatus, the combination of the casing, the whole segments, the alternate divided segments provided with grooves to receive the spokes, the lower portions of which are fixed, a chain connecting the upper ends of the whole segments and the upper divided segments together, and means for lifting the former and latter, substantially as set forth.
17. In a mold apparatus, the combination of the casing, the inner segments, alternate ones of which have wedge-shaped ends, wedge-rings engaging said ends, hooked rods secured at their upper ends to the upper wedge-ring, the hooked ends engaging the under side of the lower wedge-ring, and means for releasing the hooks of said rods from the lower wedge-ring, substantially as and for the purpose set forth.
18. In a mold apparatus, the combination of the casing, the inner segments, alternate ones of which have wedge-shaped ends, wedge-rings engaging said ends, hooked rods secured at their upper ends to the upper wedge-ring, the hooked ends engaging the under side of the lower ring, a sliding bar having a projection engaging one of the hooks, and a bell-crank, to one end of which said bar is pivoted, the other end of said bell-crank having engagement with the other hook, substantially as and for the purpose set forth.

JAS. W. HILL.
